INVALID'S CANE

Laura B. Schroeder, Milwaukee, Wis.

Application December 26, 1947, Serial No. 143,339

Term of patent 14 years

(Cl. D88—4)

To all whom it may concern:

Be it known that I, Laura B. Schroeder, a citizen of the United States and resident of Milwaukee, in the county of Milwaukee and State of Wisconsin, have invented a new, original, and ornamental Design for an Invalid's Cane, of which the following is a specification, reference being had to the accompanying drawing, forming part thereof.

In the drawing,

I claim:

The ornamental design for an invalid's cane, as shown.

LAURA B. SCHROEDER.
